UNITED STATES PATENT OFFICE.

WILLIAM E. SHARP, OF CHICAGO, ILLINOIS, ASSIGNOR OF ONE-HALF TO
GEORGE B. ROBBINS, OF HINSDALE, ILLINOIS.

FULCRUM-POST FOR BRAKE-BEAMS.

No. 800,409.

Specification of Letters Patent.

Patented Sept. 26, 1905.

Application filed July 10, 1905. Serial No. 269,020.

To all whom it may concern:

Be it known that I, WILLIAM E. SHARP, a citizen of the United States, residing at Chicago, in the county of Cook and State of Illinois, have invented certain new and useful Improvements in Fulcrum-Posts for Brake-Beams, of which the following is a specification.

My invention relates to the art of brake-beams for railway-cars, and has reference more particularly to a new and improved construction of fulcrum-posts for operating the brake-lever.

More specifically, my invention pertains to that class of fulcrum-posts adapted to accommodate interchangeably right-hand or left-hand brake-levers.

The principal object of my invention is to provide a simple and compact fulcrum-post in which the brake-lever may be readily changed from right to left without necessitating the removal of the post from the brake-beam and without necessitating the separation and reuniting of positively-connected parts.

To this and other minor ends my invention consists, substantially, in a skeleton frame having right and left hand diagonal passage-ways to accommodate the lever, in combination with removable lever-supporting plates interfittingly engaging the members of the post-frame in such a manner that they may be readily removed and changed from a position within one of the passage-ways to a corresponding position within the other, said plates being so engaged with the frame of the post that when the lever is in position they are incapable of displacement or removal; but when the lever is removed they may be readily withdrawn for the purpose of readjustment.

My invention will be readily understood when considered in connection with the accompanying drawings, which illustrate the preferred mechanical embodiment thereof, and wherein—

Figure 1 is a plan view of a fragment of a brake-beam, showing my improved fulcrum-post mounted thereon. Fig. 2 is an end view of the brake-beam, showing the fulcrum-post in side elevation. Fig. 3 is an outer end view of the post as mounted upon the brake-beam, and Fig. 4 is a cross-sectional view on the line 4-4 of Fig. 2.

Referring to the drawings, 10 designates a 55 brake-beam of the common I-beam formation, to the center of which the fulcrum-post is applied.

11 designates as an entirety the preferably integral frame of my improved fulcrum-post. More specifically describing the latter, 11^a designates an inner end plate having inwardly-turned rectangular ears 11^b, that snugly engage the flange and web of the beam, being secured thereto by a bolt or 60 rivet 12. Projecting from the outer face of the end plate 11^a are four equally-spaced parallel posts 11^c, disposed ninety degrees apart, said posts being rigidly united at their outer ends by an end plate 11^d. For 65 the sake of lightness the two end plates 11^a and 11^d may be snugly apertured, as shown at 11^e and 11^f, respectively, Figs 4 and 3. The inner faces of the posts 11^c are preferably formed by a pair of plane surfaces 70 disposed at right angles to each other, thus giving the inner sides of the post the rectangular formation of cross-section clearly shown in Fig. 4. The described construction of the frame of the post results in the formation of 75 a pair of oblique or diagonal passage-ways 12 and 13 therethrough disposed at right angles to each other.

14 and 15 designate a pair of symmetrical companion plates constituting the members 80 to and between which the brake-lever 16 is directly pivoted. These plates are of a length corresponding to the length of the passage-ways 12 and 13 from end to end of the post and are of a width preferably 85 slightly less than the full width of said passage-ways, as clearly indicated in Figs. 1 and 4, respectively. Each plate has formed on and preferably integral with its outer or back side a rectangular projection 14^a and 90 15^a, respectively, which, for the sake of lightness, is preferably cast hollow, as shown in Fig. 4. These projections are of proper size and form to just fit in and fill the spaces formed or bounded by adjacent posts 11^c and 95 the end walls 11^a and 11^d. Centrally of the plates and their projections are formed holes which receive a fulcrum-pin 17, passed therethrough and through a corresponding registering hole in the brake-lever. Said fulcrum-pin has the usual head 17^a at one end and cotter-pin 17^b at the other end, whereby when inserted it is retained in place. 100 105

In order to preserve the same form, size, and dimensions in the four posts 11^c, and consequently insure equal strength and rigidity in all of said posts, the passage-ways 12 and 13 lie at right angles to each other and each inclined forty-five degrees from the vertical, as herein shown. Inasmuch as in standard practice the brake-lever is inclined forty degrees from the vertical I provide for this variation by inclining the inner faces of the pivoted plates 14 and 15 five degrees out of parallelism with the outer faces or walls of the passage-ways, as clearly shown in Fig. 4, thereby forming one edge of said plates somewhat thicker than the other edge. By then placing the two plates inversely their two inclined faces may be brought into parallelism with each other and with the sides of the brake-lever when the same is inclined forty degrees from the vertical. Of course by forming the passage-ways 12 and 13 at angles of forty degrees from the vertical on either side fulcrum-plates 14 and 15 of uniform thickness would suffice, and such a construction I regard as entirely within the principle of my invention. As above stated, the form and construction shown and described are preferred on account of affording greater compactness and uniformity of size, form, and strength in the several parallel frame members of the fulcrum-post.

In assembling the parts one of the members 14 or 15 is introduced to the passage-way 13 and secured in place by pressing the same against one wall of the passage-way, with the extension 14^a or 15^a occupying space between the adjacent fulcrum-posts. The other plate may then be inserted similarly on the opposite side. When both plates are in position, as shown in Fig. 4, a space is provided between them for the introduction of the brake-lever, which is secured therein by the insertion of the pivot-pin 17, the latter being locked in place by the insertion of the cotter-pin 17^b. When it is desired to shift the brake-lever to the opposite side, the fulcrum-pin is withdrawn, the lever is then withdrawn, the plates 14 and 15 are withdrawn one at a time, and the parts are then reassembled in the passage-way 12 in precisely the manner already described. The integral end plate 11^d forms a closure for the end of the post, preventing possibility of longitudinal displacement of the fulcrum-plates 14 and 15, which latter, it will be observed, are always inserted and withdrawn laterally of the post. It will also be observed that when the brake-lever is in position it is impossible for the fulcrum-plates to become displaced or withdrawn by reason of their interfitting engagement with the inner faces of the fulcrum-posts 11^c.

From the foregoing it will be observed that my invention provides a simple, economical,

and easily assembled and adjusted fulcrum-post adapted to accommodate with equal facility either a right-hand or left-hand brake-lever. It also does away with the necessity of screws, bolts, and similar uniting devices for retaining the parts in co-operative relation when assembled, permitting the reassembling and adjusting of the parts without requiring the use of tools for manipulating said uniting devices.

It is evident that variations and modifications in the forms and relative arrangements of the several parts described and shown may be made by those acquainted with the art without departing from the principle or sacrificing any of the advantages of the invention. Hence I do not limit the invention to the detail features shown and described except to the extent indicated in specific claims.

It is of course evident that the principle of the invention as represented by the laterally insertible and removable fulcrum-plates might be embodied in a fulcrum-post adapted for the accommodation of the brake-lever in but a single direction.

I claim—

1. A fulcrum-post for brake-beams comprising a skeleton frame adapted to be secured to the brake-beam, said frame having a passage-way for the brake-lever formed therein, in combination with a pair of removable fulcrum-plates adapted to lie against the walls of said passage-way and interfittingly engage the frame of the post and serving to pivotally support the brake-lever between them, substantially as described.

2. A fulcrum-post for brake-beams comprising a skeleton frame adapted to be secured to the brake-beam, said frame having a pair of right and left passage-ways formed therein, in combination with a pair of removable fulcrum-plates adapted to be mounted in either of said passage-ways and to pivotally support the brake-lever between them, substantially as described.

3. A fulcrum-post for brake-beams comprising a skeleton frame adapted to be secured to the brake-beam, said frame having a pair of intersecting right and left passage-ways formed therein, in combination with a pair of removable fulcrum-plates adapted to lie against the opposite walls of either of said passage-ways and provided with projections adapted to engage the walls of the intersecting passage-way, said fulcrum-plates pivotally supporting the brake-lever between them, substantially as described.

4. A fulcrum-post for brake-beams comprising a skeleton frame adapted to be secured to the brake-beam, said frame having a pair of right and left passage-ways formed therein intersecting each other at an angle of ninety degrees, in combination with a pair of

removable fulcrum-plates adapted to lie against the opposite walls of either of said passage-ways and provided on their backs with projections adapted to engage the walls of the intersecting passage-way, said fulcrum-plates pivotally supporting the brake-lever between them, substantially as described.

5. A fulcrum-post for brake-beams comprising a skeleton frame adapted to be secured to the brake-beam, said frame having a pair of right and left hand passage-ways formed therein intersecting each other at an angle of ninety degrees, each of said passage-ways being inclined forty-five degrees from the vertical, in combination with a pair of removable fulcrum-plates adapted to lie against the opposite walls of either of said passage-ways and provided on their backs with projections adapted to engage the walls of the intersecting passage-way, said fulcrum-plates having inversely-disposed inner faces inclined to the planes of the walls of the passage-way and pivotally supporting the brake-

lever between them, substantially as described.

6. A fulcrum-post for brake-beams comprising four separated parallel frame-posts connected at both ends by transversely-disposed plates, thereby forming a pair of intersecting passage-ways formed therethrough laterally, in combination with a pair of laterally insertible and removable fulcrum-plates adapted to lie against the opposite walls of either of said passage-ways and provided on their backs with projections adapted to engage the walls of the intersecting passage-ways, said fulcrum-plates pivotally supporting the brake-lever between them, substantially as described.

In testimony that I claim the foregoing as my invention I have hereunto subscribed my name in the presence of two witnesses.

WILLIAM E. SHARP.
